UNITED STATES PATENT OFFICE.

HENRY A. DAVIS, OF KALAMAZOO, MICHIGAN.

LIQUID-FUEL BURNER.

1,223,478.

Specification of Letters Patent. Patented Apr. 24, 1917.

Application filed July 31, 1916. Serial No. 112,321.

To all whom it may concern:

Be it known that I, HENRY A. DAVIS, a citizen of the United States, residing in the city and county of Kalamazoo, State of Michigan, have invented certain new and useful Improvements in Liquid-Fuel Burners, of which the following is a specification.

This invention relates to improvements in liquid fuel burners.

10 The main object of this invention is to provide an improved wickless blue flame liquid fuel burner, applicable to a cooking stove and one which is very efficient in operation and quite compact and simple in 15 construction.

Further objects, and objects relating to details and economies of construction and operation will definitely appear from the detailed description to follow.

20 I accomplish the objects of my invention by the devices and means described in the following specification. The invention is clearly defined and pointed out in the claims.

A structure which is a preferred embodiment of my invention is illustrated in the accompanying drawing, forming a part of this specification, in which:

Figure I is a plan view of my improved liquid fuel burner, showing the same applied 30 to a cooking stove.

Fig. II is an enlarged detail vertical section through my improved burner, showing the arrangement of the various parts and the connection of the same to the stove, 35 taken on line 2—2 of Figs. I and III.

Fig. III is an enlarged detail vertical section, showing further details of the various parts taken on the section line 3—3 of Figs. I and II.

40 Fig. IV is an enlarged detail horizontal sectional view, showing the arrangement and disposition of the priming cup or trough, taken on line 4—4 of Figs. II and III.

45 In the drawing, similar reference characters refer to similar parts throughout the several views, and the sectional views are taken looking in the direction of the little arrows at the ends of the section lines.

50 Referring to the numbered parts of the drawing, I provide a cup-like body 1, a perforated top 2, and a generator 3. The generator 3 is disposed within the top in a spaced relation to the top and side walls 55 thereof and depends into the body 1 in a spaced relation to its walls, these parts co-

acting to provide an annular generating and combustion chamber. The top 4 of the generator 3 is preferably conical and is preferably provided with a central generating cup 60 60, the cup being formed by depressing a portion of the top, as clearly shown in Fig. II.

The perforations 5 of the top 2 provide means for delivering air to the annular generating and combustion chamber space between the generator and body and top. The generator is supported by the ribs 8 on the body 1 which are shouldered to receive it. The top has a central raised portion 7 above the generating cup 6 to which the delivery 70 coupling 29 is connected. A feed valve 30 is arranged between this delivery connection and the supply pipe 31.

The top 2 is provided with outwardly projecting flanges 11 at its lower end which 75 rest on the edges of the side wall 10 of the body. The top is held in place by the outer casing 12 which surrounds and incloses the front portion of the burner base and clamps the flange 11 between it and the edge of the 80 wall 10, as shown.

The body 1 is secured to the top 14 of the stove by means of the ears 13 on the body and the bolts 15. The flange 11 of the top is clamped between the top of the stove and 85 these ears 13.

The stove top is recessed to receive a part of the burner body, as shown in Fig. I, and is provided with an extension 16 having ears 17 to which the ears 18 on the casing 12 90 are secured by the bolts 19.

The priming cup member 20 is secured to the bottom of the body so that its cup 26 is below the slot-like delivery opening 27 of the body, the cup being trough-shaped, as 95 best shown in Fig. IV. This priming cup member is secured to the body 1 by means of the screws 21. The priming cup member has an extension 23 which coacts with an extension 24 projecting through the casing 100 to provide an auxiliary air inlet passage 25. At its inner end the priming cup member has a slot-like discharge opening 22 delivering below the bottom of the body.

The body 1 casing member 12 and extension 16 of the stove form a discharge passage 28 delivering to the fire-pot. This fire-pot is provided with the usual discharge flue 32 which is of importance in that it insures the proper down draft of the flame. 105 110

With the parts thus arranged, the operation is as follows: The valve 30 is opened

until a sufficient quantity of liquid fuel is delivered to fill the priming cup 26. The valve is then closed and the fuel in the priming cup ignited, preferably by the aid of a little alcohol which can be introduced through the passage 25 or through the perforations in the top. The burning of the fuel in this priming cup heats the burner to such an extent that when fuel is again turned on it is vaporized and may be ignited. The draft carries the flame downward under the generator and through the discharges 27 and 22 into the passage 28 and into the fire-pot of the stove. When the burner is well started the fuel is vaporized in the generating cup 6 and is even partially vaporized before it reaches this cup owing to the connection 29 becoming more or less heated. It is mixed with air as it passes down over the generator and burns in the annular combustion chamber formed by the generator and the body and top members, as described, and as it passes below the generator to the discharge opening 27 and through the discharge passage 22 into the passage 28. The auxiliary air admitted at 25 insures a very perfect and efficient combustion.

I contemplate that in certain circumstances air may, with advantage, be supplied at 25 under pressure securing a blow pipe action.

My improved burner is very efficient and fuel is consumed with practically no deposit.

I have not attempted to illustrate or describe certain modifications in structural details which I contemplate or which might be necessary or desirable to embody my improvements in particular embodiments, as I believe the disclosure made will enable those skilled in the art to which my invention relates to embody or adapt the same as conditions may require.

Having thus described my invention, what I claim as new and desire to secure by Letters Patent, is;

1. In a liquid fuel burner, the combination with a stove comprising a fire-pot provided with a discharge flue, of a cup-like body having an elongated discharge opening in its bottom, a foraminated top, a generator having a centrally disposed generating cup in its top disposed within said top in a spaced relation thereto and depending within said body in a spaced relation to its walls, means for feeding fuel to said generating cup, a priming member mounted below said body member and having a trough-like priming cup disposed below said discharge of said body, there being an auxiliary air inlet at the outer end of said priming cup member and a slot-like discharge at its inner end below said body, and a casing embracing said priming cup member and the front portion of said body and spaced from

the bottom thereof and coacting therewith to provide a discharge passage delivering to said fire-pot, the said auxiliary air inlet opening being at the outside of the casing.

2. In a liquid fuel burner, the combination with a stove comprising a fire-pot provided with a discharge flue, of a body having a discharge opening in its bottom, a foraminated top, a generator disposed within said top in a spaced relation thereto and depending within said body in a spaced relation to its walls, means for feeding fuel to said generator, a priming member mounted below said body member and having a priming cup disposed below said discharge of said body, there being an auxiliary air inlet at the outer end of said priming cup member and a discharge at its inner end below said body, and a casing member embracing said priming cup and the front portion of said body and spaced from the bottom thereof and coacting therewith to provide a discharge passage delivering to said fire-pot, the said auxiliary air inlet opening being at the outside of the casing.

3. In a liquid fuel burner, the combination of a cup-like body having an elongated discharge opening in its bottom, a foraminated top, a generator having a centrally disposed generating cup in its top disposed within said top in a spaced relation thereto and depending within said body in a spaced relation to its walls, means for feeding fuel to said generating cup, and a priming cup member disposed below said body and having a trough-like priming cup disposed below said discharge of said body, there being an auxiliary air inlet at the outer end of said priming cup member and a slot-like discharge at its inner end below said body.

4. In a liquid fuel burner, the combination of a body having a discharge opening in its bottom, a foraminated top, a generator disposed within said top member in a spaced relation thereto and depending within said body in a spaced relation to its walls, means for feeding fuel to said generator, and a priming cup member disposed below said body and having a priming cup disposed below said discharge of said body, there being an auxiliary air inlet at the outer end of said priming cup member and a discharge at its inner end below said body.

5. In a liquid fuel burner, the combination of a body having a discharge opening in its bottom, a foraminated top, a generator disposed within said top in a spaced relation thereto and depending within said body in a spaced relation to its walls, means for feeding fuel to said generator, and a priming cup disposed below said discharge of said body.

6. In a liquid fuel burner, the combination of a body having a discharge opening in its bottom, a foraminated top, a gener-

ator disposed within said top in a spaced relation thereto and depending within said body in a spaced relation to its walls, means for feeding fuel to said generator, and a member disposed below the discharge of said body and having an auxiliary air inlet at its outer end and a discharge at its inner end below said body.

In witness whereof, I have hereunto set my hand and seal in the presence of two witnesses.

HENRY A. DAVIS. [L. S.]
